HAIR WINDER

Filed June 29, 1926

INVENTOR

Carl Mack

UNITED STATES PATENT OFFICE

CARL MACK, OF NEW YORK, N. Y., ASSIGNEE, BY MESNE ASSIGNMENTS, TO SAMUEL BONAT AND HARRY BONAT, CONSTITUTING THE FIRM OF SAMUEL BONAT & BRO., OF NEW YORK, N. Y.

HAIR WINDER

Application filed June 29, 1930. Serial No. 119,358.

This invention relates to hair winders and has particular reference to a device which may be used in conjunction with a hair curling rod, whereby the hair can be wound more uniformly and tightly than has been possible by the methods heretofore employed in the process of hair dressing commonly known as permanent waving. In the present methods of hair winding, 10 the hair is wound and held in place by the fingers during the winding operation so that the uniformity and the degree of tightness of the winding is dependent solely upon the skill of the operator and usually 15 takes considerable time when done carefully.

Among the advantages of the hair winder of this invention is that the winding of hair may be done rapidly and uniformly 20 by a relatively unskilled operator, and so that the proper degree of tightness is uniformly maintained for each turn of the lock of hair around the curling rod. This advantage is effected by a proper degree of 25 friction between the winder and the curling rod, whereby an even tension upon the hair is maintained during the winding operation.

Another important advantage of the new 30 device is found in the process of dressing short or bobbed-hair, in that the winder may be left upon the tip of the curling rod after the hair has been completely wound 35 upon it so as to act as a clip for the ends of the strands of hair, thus eliminating the use of a separate clip for that purpose.

The new hair winder consists substantially of a sleeve adapted to cooperate with a curling rod, and which is provided with 40 a projecting member under which the lock of hair is introduced and thus held between it and the curling rod, and, as the winder is subsequently moved with a spiral motion in either direction along the curling rod, 45 the hair is smoothed as it is uniformly and tightly coiled around the latter.

For a better understanding of the invention, reference may be had to the accompanying drawings, in which

50 Figure 1 is a view of the hair winder

of this invention mounted upon the curling rod, showing the beginning of the hair winding operation;

Fig. 2 illustrates the manner in which the hair is wound and gripped after winding; 55

Fig. 3 is an enlarged view showing the hair winder in longitudinal section taken along line 3—3 of Fig. 4 and illustrating the smoothing action; and

Fig. 4 is a cross-section of the hair winder 60 taken along the line 4—4 of Fig. 3.

Referring to Fig. 1, numeral 1 designates the hair winder sleeve, 2 the attached hook or finger forming a slot under which the lock of hair is passed so as to lodge in 65 recess 3. Collar 4 is slidably mounted upon sleeve 1 and is adapted to fit under finger 2 when advanced to grip the ends of the lock of hair in recess 3 when the winding operation is completed. As illustrated in 70 Fig. 2 and by the cross-section in Fig. 4, collar sleeve 1 is provided with a slot 5 into which the guide pins 6 of collar 4 project. A spring friction clip 7 is attached to sleeve 1 and engages the outer surface of collar 75 4 so as to hold it in position upon sleeve 1.

The winder sleeve 1 is fitted upon the curling rod 8, and is provided with an internal spring 10 which is adapted to produce considerable friction between the 80 winder and the rod, so that a uniform tension is imparted to the lock of hair as it is tightly wound around rod 8. Rod 8 is provided with a slot 9 which is adapted to be placed adjacent the roots of the hair 85 and through which the lock of hair is initially passed before being inserted in the winder, and which also holds one end of the lock during and after the winding operation. 90

In operating the new hair winder, the lock of hair, after being previously prepared in the usual manner, is passed through slot 9 in the end of rod 8, which is placed adjacent the scalp, and through the slot under hook 2 so as to lodge in the recess 3 and thus be caught and held between the top end of sleeve 1 and rod 8 as is shown in Fig. 1. The operator then rotates sleeve 95 1 with a spiral motion, in either direction, 100

and the lock of hair slips through recess 3 and under the top portion of the sleeve to be coiled around rod 8 in as close a helix or degree of overlap as may be desired. The friction produced by spring 10 bearing against rod 8 causes the lock of hair to be wound tightly around rod 8 when the sleeve 1 is moved along the latter with a spiral motion and at the same time the inner surface of the upper portion of sleeve 1 imparts a smoothing action to the lock of hair as it is being wound by pressing it against rod 8 in the manner illustrated by Fig. 3. The tension upon the hair may be adjusted at will by varying the pressure of spring 10 upon rod 8. When the lock of hair is completely wound upon curling rod 8, collar 4 is slid over sleeve 1 into the position shown in Figs. 2 and 3, whereby the ends 20 of the hair are forced and gripped in recess 3 and the lock of hair is held as wound. The winder may then be left in this position upon rod 8 to serve as a clip for holding the ends of the hair in place during the remainder of the heating and dressing operation. These hair winders are adapted to be employed in plurality, depending upon the number of locks of hair to be dressed, and may be modified to any desirable degree 30 within the scope of the appended claims.

I claim:

1. In a hair gripping device the combination of a mandrel, a sleeve adapted to cooperate with the mandrel and having a hair embracing portion in the form of a slot, means on said sleeve for forcing the hair into the base of the slot, and means for holding the last named means in adjusted position.
2. In a hair winder, the combination of a sleeve adapted to cooperate with a curling member, means on said sleeve for receiving the hair, and a device on said sleeve for gripping the hair in said means.
3. In a hair winder, the combination of a rod, a sleeve adapted to cooperate with said rod, means upon said rod and said sleeve for receiving the hair, and a device upon said sleeve for gripping the hair to the means.
4. In a hair winder, the combination of a sleeve, a curling rod, friction means between said sleeve and the rod, means forming part of said sleeve for receiving the hair, and a clip for holding the hair in said receiving means.

CARL MACK.
